UNITED STATES PATENT OFFICE.

JOHN HOFMAN, HARRISON BUCKLIN, AND DAVID E. BURR, OF ROCHESTER, NEW YORK,
ASSIGNORS TO JOHN HOFMAN CO., OF ROCHESTER, NEW YORK, A CORPORATION OF
NEW YORK.

DOOR FOR DISPLAY-CABINETS.

1,008,266.

Specification of Letters Patent. Patented Nov. 7, 1911.

Application filed May 27, 1911. Serial No. 629,881.

To all whom it may concern:

Be it known that we, JOHN HOFMAN, HARRISON BUCKLIN, and DAVID E. BURR, each of Rochester, in the county of Monroe 5 and State of New York, have invented certain new and useful Improvements in Doors for Display-Cabinets; and we do hereby declare the following to be a full, clear, and exact description of the same, reference being had to the accompanying drawings, forming a part of the specification, and to the reference-numerals marked thereon.

Our present invention has for its object to provide an improved means for mounting 15 doors or closures for cabinets or wardrobes, such as those employed for the display of clothing or other articles of merchandise, whereby a minimum amount of floor space is occupied or required to accommodate the 20 doors during their opening and closing movement.

A further object of the invention comprehends an arrangement of parts whereby when the door is in the open position it may 25 be moved rearwardly into the case in juxtaposition to one end thereof without materially reducing the area of the interior of the cabinet or restricting the opening at the front of the cabinet.

To these and other ends the invention consists in certain improvements and combinations of parts all as will be hereinafter more 30 fully described, the novel features being pointed out in the claims at the end of the 35 specification.

In the drawings: Figure 1 is a horizontal sectional view of a display cabinet fitted with doors constructed in accordance with our present invention; Fig. 2 is a detail vertical 40 sectional view taken on the line 2^x—2^x of Fig. 1; Fig. 3 is an enlarged detail view taken on the line 3^x—3^x of Fig. 2; Fig. 4 is a detail plan view partly in section, showing a modification; and Figs. 5, 6, 7 and 8 are detail 45 views of the door fittings which coöperate with the guides.

Similar reference numerals in the several figures indicate similar parts.

In the construction of display cabinets or 50 wardrobes especially those used by clothiers

for the display of garments, one of the most important features resides in the mechanism by which the doors are mounted in the cabinet, since it is essential that the doors when opened shall not obstruct the aisle or passage way in front of the cabinet, and at the same time provide a full opening at the front of the cabinet through which the goods may be easily removed for inspection and subsequently replaced in the cabinet. The show 55 cases which are provided with glass side and top walls form an added difficulty in the way of mounting the doors since the cabinets are constructed in skeleton form and in order to maintain an advantageous display of the 60 goods contained therein, it is desirable to give the glass panels the greatest possible area. In connection with such a cabinet it is necessary to provide a means for mounting the door whereby it may be operated 65 with perfect ease and freedom, so that the necessarily light construction of the skeleton frame may not be warped or twisted or subjected to strain during the movement of the 70 doors either in the act of opening or closing 75 them.

In illustrating our present invention we have shown a cabinet comprising the rectangular base 1, which may be of any desired height, at the top and forward edge of which 80 is the inwardly extending sill 2, and having at the ends the sills 3, the intervening portion of the base being preferably covered by a flooring 4. The corners of the cabinet are formed by the vertical posts 5 at its forward 85 edge and the rear posts 6, all of which are connected at their tops by the front, rear and end rails 7, 8 and 9, respectively. The end walls of the cabinet are closed by the glass plates or panels 10, the back being 90 fitted with a similar panel 11, while the top may also be made of a heavy glass plate 12.

In the cabinet illustrated two doors are shown which, when closed, meet at the center of the cabinet and close the open front thereof, but as a single door may be used and the construction of these doors is similar, a description of one will suffice for both. The door fits the open side of the cabinet between the sill 2 and the top rail 7, and comprises 100

an open rectangular frame composed of the bottom rail 13, the top rail 14, rear rail 15, and the parting strip or front rail 16. Inset in these rails is the glass plate or panel 17. 5 The door is preferably inset a short distance within the forward edge of the sill 2 and the rail 7, as shown in Fig. 1, and the inner edge of the post 5 is provided with a projection or molding strip 18 which overlies the outer 10 edge of the rear rail 15 of the door when the latter is closed, as shown in Figs. 1 and 3. In illustrations adapted to show one embodiment of the invention, we provide a 15 means for mounting the door whereby it is so guided within the cabinet, from the time its opening movement commences, when it is rotated out of its normal position in alignment with the sill 2 and the rail 7, that as its opening movement increases and when 20 in full open position, it will not be cramped between the top and bottom walls of the cabinet and permitted to exert undue strain upon the lightly constructed parts thereof. The arrangement of the track plates or 25 guides upon which the door moves is also such that as the door commences to open it will also travel rearwardly into the casing and at no time will its major portion overhang or project beyond the front of the 30 casing.

Fitted on the top and bottom faces, respectively, of the end sill 3 and end rail 9 of the cabinet, are bottom and top guides 19 and 20, which extend rearwardly from 35 the front of the casing and preferably parallel to the end wall 10 thereof. At the corners of the door at the top and bottom are projections 21 and 22 which coöperate with these guides and serve to cause the rear end 40 of the door to be moved inwardly into the cabinet as the door is opened, as will be further described. Similar guides 23 and 24 extend along the front sill 2 and front top rails 7 to a convenient point where they 45 curve rearwardly, as indicated at 25 in Fig. 3, and thence extend parallel with and preferably adjacent to the guides 19 and 20, as indicated at 26. The bottom and top rails 13 and 14 of the door are each provided on 50 their inner faces with offset projections 27 and 28, which coöperate respectively with the guides 23 and 24, and during the opening movement of the door form fulcrums around which it is rotated, and as they slide 55 along the guideway permit the door to recede in the cabinet while it is being opened, the curve 25 in this guide permitting a pronounced rearward movement of the door at the time it approaches its full open position 60 after which it may be projected still farther into the cabinet, the several projections traveling in their respective parallel guideways. The guideways may be variously constructed, but we prefer to form them of

channel iron, which may be let into grooves 65 formed in the sills and rails of the case, as shown particularly in Fig. 2, as such bars will materially strengthen these parts and serve to stiffen them without projecting into the cabinet. The parts coöperating with 70 the guideways, which we have generally termed projections, are preferably spherical steel balls of a diameter to fit the tracks or guideways, those indicated by 21 and 22, at the corners of the door, being held in retainers 29 illustrated in detail in Figs. 5 and 6, which are fitted in suitable recesses provided in the extremities of the rear rail 15. These retainers preferably comprise a face plate having a projection thereon provided with a seat forming an annular raceway for a series of balls on which the larger ball forming the projection is seated, this arrangement of the parts permitting the door to pivot freely upon the larger balls 85 or projections, while the latter are permitted to rotate as they travel along their guideways. The other projections 27 and 28 are also formed of balls supported upon anti-friction bearings formed by grooved rollers 90 30 journaled in a caster frame 31 having the pin 32 journaled in the bearing plate 33 secured to the inner side of the top and bottom rails 13 and 14 of the door. The centers of the rollers 30, it will be noticed are so arranged that the center of the journal pin 32 is preferably forward of the center of the balls 27 and 28, so that a swinging movement of the caster frames 30 is permitted as the balls 27 and 28 travel around the 100 curved portion 25 of their guideways, the rails of the door being recessed upon their inner faces slightly to permit slight movement of the parts. The forward projections 27 and 28 are preferably arranged at the 105 side of the center of the door nearer the rear rail than they are to the parting rail, so that a lever action is provided, during the opening movement of the door which adds to the ease with which the door may be 110 opened, since its rotary movement about the projections 27 and 28 also tends to move the door inwardly. The plate glass with which the door is fitted adds considerably to its weight and to overcome any tendency 115 which the door may have to bind in the guideway by reason of its forward edge sagging, an arm or bracket is provided which forms an extended bearing for the upper rear edge of the door, and which is 120 brought into action during the opening movement of the door for the purpose of relieving the strain on the upper bearing member or projection 22, and the consequent strain which this member would naturally 125 transmit to the lightly constructed top end rail 9 of the case. This auxiliary bearing member, illustrated particularly in Fig. 2

consists of the roller 34 journaled at the extremity of a bracket 35 pivoted to a bearing 36 on the rail 15 of the door. The bracket is offset as shown in Fig. 2, so that 5 the roller 34 traverses the guide 19 during the inward and outward movement of the door, and when the latter is closed the roller 34 is near the forward side of the cabinet, and during its opening movement the door 10 rotates into alinement with the track, as shown in Fig. 3, when any tendency on the part of the door to tilt on the member 27 is resisted wholly or in part by the roller 34, which permits the projection 22 to then act 15 merely as a guiding member for the upper corner of the door, but without becoming cramped in its guideway.

A modification of the parts described which is more particularly adapted for 20 small doors, or those which are comparatively light in weight, is illustrated in Fig. 4. In this illustration a portion of the front and end sill of a wardrobe cabinet is shown and indicated by 2^a and 3^a, respectively. The view shows a horizontal section, corresponding to Fig. 3, and it will be understood that the cabinet is also provided at the top with the front and end rails. In the arrangement of the parts here illustrated, the guideway 40 in the front sill extends in a straight line to the corner of the cabinet where it meets the guide 41 in the end sill. The door, indicated by 42, is provided at the upper and lower ends of the 30 rear rail with balls or projections 43, and at about the center of its top and bottom rails the balls or projections 44 are also provided. The projections 43 and 44 may be constructed in detail as shown in Figs. 5 and 6, or 35 as shown in Figs. 7 and 8, in which latter the balls are supported loosely upon recessed rollers 45 journaled in boxes 46 on face plates 47. The door 42 arranged with the parts described operates similarly to the 40 door illustrated in Figs. 2 and 3, although it does not recede in the cabinet with the same speed as the door mounted as previously described, since it is necessary in opening the door to swing it laterally until the projections 44 have traversed the full length of the guides 40 and are in alinement with the guides 41, when the door may be projected rearwardly until it has reached the limit of its rearward movement in the cabinet.

55 Doors for cabinets mounted in the manner described operate freely without binding or cramping and as they are supported both at the top and bottom the rails may be made narrow in width thus providing a large 60 opening for the glass plate, and affording an unrestricted view of the contents of the cabinet from a point in front of the latter.

The mounting of the door in the manner comprehended in this invention, whereby

the use of a hinge connection either between 65 the door and the cabinet case or between the door and a movable carriage sliding within the case, permits the latter to be made lighter in construction throughout as strain caused by the weight of a hinged door is 70 entirely obviated. This lessening of the size of the parts also permits greater area to be given to the glass panels at the ends, back and top of the cabinet. A further advantage is found in mounting the door so that 75 it begins to recede with the commencement of its opening movement, as in this way about one-half of the door is projected within the cabinet when it has been opened the full distance. This feature particularly 80 adapts this door for use upon display cabinets which are necessarily located in places which are apt to be more or less crowded.

We claim as our invention:

1. The combination with a cabinet having 85 an open front and provided with walls at the top and bottom thereof, of a door closing said opening, coöoperating guides and projections in the cabinet and on the door permitting said door to swing and during its 90 swinging movement to move laterally and inwardly into the cabinet and an arm pivoted to the door engaging the top of the cabinet in rear of the door to support said end of the door and prevent its tilting. 95

2. The combination with a cabinet having an open front and comprising bottom and top walls and a door fitting said opening, of means for mounting the latter in the cabinet comprising guides fixed to the top and 100 bottom walls of the cabinet and projections attached to the door and coöoperating with the guides and a bearing arm hinged to the door and extending into the cabinet and having its inner end coöperating with the guide 105 on said top wall.

3. The combination with a cabinet having an open front and comprising bottom and top walls and a door fitting said opening, of means for mounting the door in the cabinet 110 comprising guides fixed to the top and bottom walls of the cabinet and projections attached to the door and coöoperating with the guides, said guides and projections being so disposed that during the opening movement of the door it is caused to slide laterally and recede into the cabinet, an arm attached to the door having an end traveling in one of the guides and forming a bearing spaced from the door. 115

4. The combination with a display cabinet open at its front side and having bottom and top walls, guides on the latter extending rearwardly into the cabinet and separate guides at the top and bottom of the cabinet 125 each having a part extending along the front of the cabinet and provided with a short rearwardly curved portion terminating in

an extremity lying in juxtaposition to the corresponding first mentioned guide, of a door, projections at its top and bottom corners engaging the first mentioned guides, 5 casters offset from the inner face of the door coöperating with the second set of guides and an arm extending inwardly from the door and coöperating with the interior of

the cabinet to prevent the door from binding in the cabinet.
